removal

UNITED STATES PATENT OFFICE.

WILLIAM HENRY HEALES, OF COVENTRY, ENGLAND, ASSIGNOR TO THE DUNLOP RUBBER COMPANY, LIMITED, OF LONDON, ENGLAND, A BRITISH COMPANY.

DETACHABLE WIRE-SPOKED WHEEL.

1,393,441.

Specification of Letters Patent. Patented Oct. 11, 1921.

Application filed January 3, 1921. Serial No. 434,672.

To all whom it may concern:

Be it known that I, WILLIAM HENRY HEALES, a subject of the King of Great Britain, residing at 573 Stoney Stanton road, Coventry, in the county of Warwick, England, have invented certain new and useful Improvements in or Relating to Detachable Wire-Spoked Wheels, of which the following is a specification.

10 This invention relates to detachable wire spoked wheels.

According to my invention the wire spoked wheels are so constructed that they may be readily used in substitution for the usual bolted detachable wheels thereby obtaining the advantages of a detachable wire spoked wheel which is interchangeable (on the same hub) with a detachable wooden or pressed steel wheel of usual type.

20 For the purpose of my invention the boss of the wire spoked wheel comprises a circular sheet metal box-like portion which is of approximately the same width as the boss of an ordinary detachable wooden or pressed steel wheel and which has a central hole fitting the cylindrical part of the hub portion carried by the axle. The said box-like portion or boss may be of U-shape in cross section closed at the mouth and suitably formed 25 or flanged at the edges for the reception of the inner ends of the wire spokes. The said box-like portion has a circular series of transverse sleeves or bushes which register with the usual annular series of retaining 30 studs or bolts on the said hub portion. The said sleeves or bushes extend from one side to the other of the said box-like portion at points corresponding with the usual attaching studs or bolts. For closing the opening 35 at the mouth of the U-shaped portion I employ a metal annulus or ring suitably applied thereto or formed in one therewith.

In order that the said invention may be clearly understood and readily carried into effect the same will now be described more fully with reference to the accompanying drawings, in which:—

Figure 1 is a transverse vertical section of the upper half of one form of the improved wheel mounted on the hub portion of the axle.

Figs. 2 to 4 are also transverse vertical sections of the upper halves of modified forms of the improved wheel.

Like letters of reference indicate similar parts in all the figures.

A is the annular U-shaped steel portion of the wheel boss constituting a circular box-like member having flanged edges a' with which the inner ends of the wire spokes c engage and also having a circular series of transverse holes provided with sleeves or bushes a^2 to receive the studs or bolts b on the hub portion B which is carried by the axle as is well understood. C is the wheel rim with which the outer ends of said wire spokes are connected in any appropriate manner. The central hole of the annular U-shaped portion A fits onto the cylindrical part b^2 of the hub portion B and the wheel 70 is held in place by nuts b' engaging with the studs or bolts b , an annular disk or washer b^2 being situated between the said nuts and the wheel boss as is usual with bolted detachable wheels of the wooden or pressed steel type. In Fig. 1 I have indicated in dotted lines the position which the usual bolted detachable wheel would occupy when used in substitution for the wire spoked wheel. A' is the metal ring or annulus for closing 80 the opening at the mouth of the U-shaped portion A. In Fig. 1 this ring engages at its edges with recesses a^3 , a^4 where it is secured by welding or other appropriate means. In Fig. 2 the aforesaid ring A' extends across the flanged edges a' of the U-shaped portion A so that the inner ends of the wire spokes pass through the said ring as well as through the flanged edges a' , and the edges of the said ring are shaped to 90 suit the form of the said flanged edges. In Fig. 3 the edges of the ring A' are bent over the flanged edges a' of the U-shaped portion A so as to completely inclose the same. In each of the forms of the improved wheel 95 illustrated by Figs. 1, 2 and 3, the space within the U-shaped portion A is shown filled with packing material a^4 which may consist of an annular block of wood. In Fig. 4 the said ring A' and the U-shaped 100 portion A are formed in one piece the meeting edges at X being joined together by welding or otherwise. Annular members A^2 , A^2 are interposed between the parts a^5 , a^6 of the U-shaped portion where they bend 105 over at the edges to form the flanges in order to impart additional strength thereto. In this figure the sleeves or bushes a^2 are of

substantial thickness and are provided with shoulders a^5 in which case the packing material a^4 can be dispensed with.

Although I have shown several examples 5 of the form which my improved wheel may take I wish it to be understood that I do not desire to confine myself thereto.

What I claim and desire to secure by Letters Patent of the United States is:—

- 10 1. A detachable wire spoked wheel in which the boss consists of a circular sheet metal box-like portion of approximately the same width as the boss of an ordinary detachable wooden or pressed steel wheel and having a central hole fitting the cylindrical part of the axle, outwardly directed peripheral flanges on said circular portion to which the inner ends of the wire spokes are connected and a circular series of sleeves 15 situated within said circular box-like portion and adapted to register with the existing attaching bolts for retaining the wheel in place.
- 20 2. A detachable wire spoked wheel, in which the boss consists of a circular sheet metal box-like portion suitably formed at the periphery for the reception of the inner ends of the wire spokes and having a central hole fitting the cylindrical part of the 25 axle and also a circular series of holes surrounding said central hole for the reception of retaining bolts.
- 30 3. A detachable wire spoked wheel in

which the boss consists of an annular sheet metal U-shaped portion suitably formed at 35 the periphery for the reception of the inner ends of the wire spokes and having at its base a central hole fitting the cylindrical part of the axle and also having a circular series of sleeves surrounding said central 40 hole for the reception of retaining bolts.

4. A detachable wire spoked wheel in which the boss consists of an annular sheet metal U-shaped portion suitably formed at the periphery for the reception of the inner 45 ends of the wire spokes and having at its base a central hole fitting the cylindrical part of the axle and also having a circular series of sleeves surrounding said central 50 hole for the reception of retaining bolts, and a metal ring at the mouth of said U-shaped portion.

5. A detachable wire spoked wheel in which the boss consists of an annular sheet metal U-shaped portion flanged at the periphery for the reception of the inner ends 55 of the wire spokes and having at its base a central hole fitting the cylindrical part of the axle and also having a circular series of sleeves surrounding said central hole for the 60 reception of retaining bolts, and a metal ring at the mouth of said U-shaped portion with its edges extending over the flanged periphery.

WILLIAM HENRY HEALES.
